UNITED STATES PATENT OFFICE.

CARL MOLDENHAUER, OF FRANKFORT-ON-THE-MAIN, GERMANY.

PRECIPITATING PRECIOUS METALS OUT OF THEIR SOLUTIONS.

SPECIFICATION forming part of Letters Patent No. 512,046, dated January 2, 1894.

Application filed August 19, 1893. Serial No. 483,574. (No specimens.)

To all whom it may concern:

Be it known that I, CARL MOLDENHAUER, a subject of the Emperor of Germany, and a resident of Frankfort-on-the-Main, Germany, 5 have invented certain new and useful Improvements in Precipitating Precious Metals out of their Solutions, of which the following is a specification.

The process consists in the use of aluminum for the industrial precipitation of gold and other precious metals out of cyanide-solutions in the presence of free alkali or earth alkali.

Hitherto zinc has been used for the industrial precipitation of gold out of the cyanide solutions which have been obtained by dissolving the gold from its ores by means of a solution of cyanide of potassium. But when used for the purpose in question the zinc shows considerable disadvantages. I have found 20 that these disadvantages are avoided if aluminum is used for the purpose in question. While zinc enters into combination with the bound or free cyanide of alkali contained in the cyanide-solutions according to the formula:

the aluminum precipitates the gold out of its cyanide solution without entering into combination with the cyanogen, but enters only into reaction with the simultaneously present caustic alkali.

The process is the following: By dissolving gold out of its ores by means of cyanide of potassium in the presence of an oxidizing agent a solution is obtained according to the formula:

If to this cyanuret-of-gold-solution, which contains free alkali, aluminum is added, the following reaction takes place:

The free cyanic acid which is formed accord-

ing to this formula combines at once with the free alkali present to form cyanide of potassium according to the following formula:

50

By the action of aluminum therefore the cyanide of potassium which has been used for 55

dissolving the gold out of its ores, is regenerated, which is not the case when zinc is used.

But the zinc does not confine itself to enter into combination with the cyanogen of the cyanuret-of-gold-solution, but it attacks also 60

the free cyanide of potassium which is still contained in the solution, whereby this free cyanide of potassium is consumed to a great part, which is also not the case with aluminum.

These facts are, for the use of the waste solution 65

for a new extraction of gold, of great importance inasmuch as by this the whole cyanogen of the regenerated and remaining free cyanide of potassium can at once be used anew, while the solutions which are obtained by the use of 70

zinc are not of so great an advantage. Trials for regenerating them have often been made, but they are comparatively dear. Therefore

it is clear that by the use of aluminum a great saving of cyanide of potassium is attained. 75

In fact only that part of cyanide of potassium needs to be replaced, which has been lost mechanically and which has been decomposed by alien influences. To this great and essential

advantage of the aluminum some other ones 80

join. The aluminum is much less subject to oxidation than the zinc, so that it can be sent from the place of its production in that form

in which it has to be used for the precipitation, while in the use of zinc it is regarded as 85

a great advantage to bring it into the required form at the place of its use and immediately before its use. For the same reason also the

repeated use of the aluminum for continued precipitations is admissible. Finally for the 90

precipitation of one and the same quantity of

precious metal four times less aluminum than

zinc is required.

It is known to me that aluminum has already

been used for precipitating precious metals out of acid or neutral solutions, but in such cases its use has no advantages over the use of zinc and iron. But the industrial precipitation of the precious metals out of alkaline cyanide-solutions by means of aluminum has not yet been known and it was not known too that by the use of aluminum in the presence of free alkali the above mentioned essential advantages can be obtained.

I do not confine myself to any special form in which the aluminum has to be used, as it can be used in any suitable form.

What I claim, and wish to be secured by United States Letters Patent, is—

Precipitating gold and other precious metals out of their cyanide-solutions by treating the latter with aluminum in the presence of a free alkali as and for the purpose set forth.

In testimony that I claim the foregoing as my invention I have signed my name in presence of two subscribing witnesses.

CARL MOLDENHAUER.

Witnesses:

CARL FEHR,

FRANK H. MASON.
